UNITED STATES PATENT OFFICE.

GRAHAME B. RIDLEY, OF SAN FRANCISCO, CALIFORNIA, ASSIGNOR TO EDWARD B. WARD, OF SAN FRANCISCO, CALIFORNIA.

DESICCATOR.

Application filed October 22, 1924. Serial No. 745,103.

This invention relates to a desiccator of the bin type and particularly pertains to a means of dehydrating articles such as nuts, fruits and the like.

5 It is the principal object of the present invention to provide a desiccator of the bin type which will operate to rapidly and thoroughly dehydrate fruits, nuts, vegetables, and the like in a substantially continuous operation, and which is provided with means for insuring that the volume of material in the bin will be uniformly dehydrated irrespective of its position in the bin.

The present invention contemplates the use of bins into the top of which material to be desiccated may be delivered, and from the bottom of which it may be withdrawn, said bins being further constructed with means for creating a transverse circulation 20 of air through and cross the bin in a desired direction, said directions being readily controlled as the drying proceeds.

The invention is illustrated by way of example in the accompanying drawings, in 25 which:

Fig. 1 is a view in side elevation illustrating the complete apparatus with which the present invention is embodied.

Fig. 2 is a view in plan illustrating the 30 present invention.

Fig. 3 is an end view of the structure with parts broken away to more clearly show the construction of one of the bins and the manner of controlling the transverse flow of air across a bin.

Fig. 4 is a view in end elevation showing the furnace forming a part of the present invention, and the manner in which this furnace is connected with the bins.

40 Fig. 5 is a view in side elevation showing a form of bin having a vertical air circulation.

Fig. 6 is a view in central vertical section through the structure shown in Fig. 5 as 45 viewed on line 6-6.

Referring more particularly to Figs. 1 to 4 of the drawings, 10 indicates a subframe structure supporting a plurality of bins 11. There are three bins shown in the drawing, 50 although it will be understood that the device may be of any capacity. The bins are separated from each other by vertical partition walls, and may be separately closed by swinging doors 12. These doors are fitted 55 with counterbalances as indicated at 13 to

facilitate in readily swinging them to their opened positions, and holding them in said positions as more clearly indicated in Fig. 3.

The opposite side walls of the bins are formed of reticulated material such as the 60 screen wire indicated at 14 in Fig. 3, as this construction makes it possible to effect a horizontal passage of air across the bins, and for that reason frusto-conical air chutes 15 and 16 are formed at the opposite ends with 65 their large ends registering with the outer surface of the screen wire 14. Their restricted portions are in communication with air ducts 17 and 18, the arrangement of which is more clearly shown in Fig. 2 of the 70 drawing. By reference to this figure, it will be seen that the cross sectional area of the ducts is reduced along the length of the ducts, so that a uniform volume of air may be delivered to and removed from each of 75 the bins.

By reference to Fig. 3, it will be seen that the frusto-conical air feed chutes are disposed one above the other, and are of dimensions to insure that a constant supply of air 80 delivered through both of the chutes will be distributed substantially over the entire side wall 14, and will pass therethrough to come into intimate contact with the material in the bin. It may be desirable to vary the 85 volume of air flowing to different portions of the bin or to discontinue its flow entirely, and this may be brought about by disk valves 19 and 20 which may be brought to close the throats of the chutes 15 and 16 respectively. 90

These valves are mounted on valve stems 21. The valve stems are mounted for longitudinal reciprocation, and may be actuated by sprockets 22 having threaded portion 23 receiving the threaded extensions of the valve 95 stems 21 so that the stems may be longitudinally reciprocated as the sprockets are rotated. Operating chains 24 and 25 are provided for the sprockets.

The bottoms of the bins are formed with 100 inclined floors, at the centers of which are draw-off openings 26. These openings communicate with chutes 27 normally closed by doors 28. By this means the contents of a bin may be readily withdrawn. A sliding 105 door 29 normally closes the central opening in the floor, and is operated by a threaded control shaft 30 which is rotated by a hand wheel 31.

Material to be dehydrated may be con- 110

veniently fed into any one of the hoppers by the elevating conveyor structure 32 which comprises a lower sprocket 33, an upper sprocket 34, and a conveyor chain 35. 5 Mounted on this conveyor chain are elevator buckets 36. These buckets may be filled with material from a loading platform 37, and may be emptied onto a swinging chute 38 as the buckets pass over and around the upper sprocket 34. As will be understood from an examination of Fig. 3, the chute 38 may swing horizontally on its pivot 39, and may deliver material into any one of the bins desired. 10

15 The heating and circulation of air through the bins is brought about by the action of a furnace 40 and a blower 41. The furnace is preferably formed with a fire box 42 within which an oil burner 43 operates. The fire box 20 communicates with a stack 44 through a plurality of flue pipes 45, as indicated by dotted lines in Fig. 4. These pipes cause the products of combustion to pursue a circuitous path of travel through the upper part of 25 the furnace circuit, and thus insure that a maximum amount of heat will be imparted to the surrounding air which is to be passed through the dehydrating bins. The lower portion of the furnace jacket is connected with a blower 41 which may be driven by 30 any suitable source of power. This blower is fitted with a vertical duct 46 extending to a point substantially on the level with the bins. 35

40 A Y-shaped air conduit communicates with the upper end of the duct 46, as more clearly shown in Fig. 2 of the drawings. The leg 47 of this member connects with the supply pipe 17 extending horizontally along one side of the bins, while the supply pipe 18 extends horizontally on the opposite side of the bins. 45

45 Communicating with this Y-shaped conduit at a point between the portions 47 and 48, is a stack 49. This stack extends vertically, one portion of it projecting above the bins and the other portion forming a Y as indicated at 50 in Fig. 4. This Y connects with the furnace jacket upon the opposite side from the blower 41. A deflector damper 51 is disposed in the throat of this Y and deflects any desired amount of the air which 50 has passed through the bins downwardly into the furnace, at the same time permitting air to be drawn in from the vertical portion of the stack 49. A horizontally swinging deflector damper 52 is mounted in the Y, of which legs 47 and 48 are a part, and may be actuated by a rod 53 to divert the heated air 55 to either side of the bins. Thus it is possible to reverse the direction of circulation of the air through the bins, and thereby expose the entire mass to the intimate action of the dry heated air passing into the bins. 60

65 It would be evident that if the air passed

through the bins in one direction only, the air would gradually become laden with moisture as it progressed in its flow, with the result that the air would be lowered in temperature as it progressed in its flow. 70

In operation of the present invention, material is placed in the bins by delivering it to the elevator buckets 36, which in turn dump the material onto the swinging chute 38. This chute may be manipulated to divert the 75 material to any one of the bins. After the bins are filled, the covers 12 may be swung downwardly to a closed position and locked by staple locks as indicated at 54 in the drawing. 80

The blower 41 may then be started to draw heated air from the furnace 40 and to force it upwardly through the duct 46. The horizontal damper 52 may then be positioned to either divert heated air to the leg 47 of the 85 Y or the leg 48. 90

Assuming, for example, that it is diverted to the leg 47 of the Y, as indicated in Fig. 2, it will be evident that this heated air will then pass to the distributing pipe 17 and will 90 be forced into the bins through their foraminous side walls in such proportion as permitted by the positions of the valve disks 19 and 20 of the respective bins. 95

This air will then be forced across the bins 100 and in intimate contact with the material to be dehydrated. It will be evident that the quantity of material in the bins and the length of travel of the air through the material will have a direct bearing upon the 105 desiccating action brought about, and for this reason, the bins have been designed to insure that a maximum dehydrating action will be effected before the air becomes objectionably laden with moisture. After the 110 air has passed through the bin, it may then pass out into the passageway 18 and then return through the pipe to the center of the Y. Here it will encounter the horizontal damper 52, and will be directed to the stack 115 49. If the stack chamber 51 is in the position shown in Fig. 1 of the drawing, the entire volume of air will pass out into the atmosphere, but if this damper is elevated, a proportionate amount of air will be diverted 120 downwardly into the Y 50 and to the furnace. 125

In the event that fresh air is desired to supplement some of the air forced out through the stack, sliding draft plates 55 120 in the walls of the Y 50 may be opened to permit fresh air to be drawn to the bottom of the furnace. 130

By reference to Figs. 5 and 6 of the drawing, it will be apparent that a slight rearrangement of the parts previously described could be made to dispose the bins so that the direction of travel of the air would be vertical instead of horizontal, as previously described. 135

It will thus be evident that the apparatus here disclosed makes it possible to readily dehydrate large volumes of material in a dehydrator of the bin type, and that the material thus treated may then be drawn off from the bottoms of the bins.

While I have shown the preferred form of my invention as now known to me, it is to be understood that various changes may be made in its construction without departing from the spirit of the invention as claimed.

Having thus described my invention, what I claim and desire to secure by Letters Patent is:

15 1. A desiccator comprising a bin adapted to receive material to be dehydrated at its top and to draw said material off therefrom at its bottom, means for creating a cross current of heated air through the bin, and means for optionally changing the direction of flow of said air current.

20 2. A desiccator comprising a bin adapted to receive material to be dehydrated at its top and to draw said material off therefrom at its bottom, means for creating a cross current of heated air through the bin, means for optionally changing the direction of flow of said air current, and means for optionally controlling the volume of air flow across said bin.

25 3. A desiccator comprising a bin adapted to receive material to be dehydrated at its top and to draw said material off therefrom at its bottom, means for creating a cross current of heated air through the bin, means for optionally changing the direction of flow of said air current, and means for optionally controlling the volume of air flow across said bin and at different levels 40 therein.

45 4. A desiccator comprising a plurality of bins, supply manifolds extending along opposite sides thereof and communicating with the several bins, and means for creating a circulation of air through the manifolds and the bins.

5. A desiccator comprising a plurality of bins, supply manifolds extending along opposite sides thereof and communicating

50 with the several bins, means for creating a circulation of air through the manifolds and the bins, and means for changing the direction of flow of air through said manifolds and bins.

6. A desiccator comprising a plurality of bins, manifold pipes extending along opposite sides thereof and communicating with said bins, a furnace with which said manifold pipes connect, and means for forcing air to circulate through said manifold 60 pipes, the bins and the furnace.

7. A desiccator comprising a plurality of bins, manifold pipes extending along opposite sides thereof and communicating with said bins, a furnace with which said manifold pipes connect, means for forcing air to circulate through said manifold pipes, the bins and the furnace, and means for changing the direction of flow of said air in its circulation through the bins.

70 8. A desiccator comprising a plurality of bins, manifold pipes extending along opposite sides thereof and communicating with said bins, a furnace with which said manifold pipes connect, means for forcing air to circulate through said manifold pipes, the bins and the furnace, means for changing the direction of flow of said air in its circulation through the bins, and means for supplying fresh air to the furnace in a desired proportion to the air being drawn 80 from the bins.

85 9. A desiccator comprising a bin, opposite walls of said bin being formed of foraminous material, a removable cover for said bin, a draw-off outlet in the bottom of the bin, air passageways at opposite sides of the bin and adapted to deliver air to the foraminous walls, and valves in said passageways for controlling the volume of air passing 90 through the walls.

10. A desiccator comprising a plurality of bins within which material to be dehydrated may be placed, means for delivering heated air to each of the bins, and means for optionally discontinuing the delivery of heated air to any one or more of the bins.

GRAHAME B. RIDLEY.
